UNITED STATES PATENT OFFICE.

WILLIAM H. MULLINS, OF SALEM, OHIO.

DESIGN FOR A BAKING-PAN.

SPECIFICATION forming part of Design No. 26,933, dated April 20, 1897.

Application filed March 3, 1897. Serial No. 625,901. Term of patent 14 years.

To all whom it may concern:

Be it known that I, WILLIAM H. MULLINS, a citizen of the United States, residing at Salem, in the county of Columbiana and State of Ohio, have invented and produced a new and original Design for Baking-Pans and Similar Utensils, whereof the following is a description, due reference being had to the accompanying drawing, which forms part of this specification and represents in perspective a baking-pan embodying the characteristic features of my design.

Reference being had to the accompanying illustration and letters thereon, it will be noted that in design my novel form of baking-pan comprises upper and lower interchangeable sections A B, which collectively constitute a rectangular figure, as shown. The leading feature of this rectangular pan re-20 sides in a series of transverse crimps or corrugations C, which are formed upon or stamped in the structure—sides, bottom, and top—in parallel adjacent planes, being so spaced and arranged as to register and completely sur-

round the pan, in conjunction with a surrounding flange D, which bisects said corrugations and constitutes a median line of demarcation between the pan-sections A B.

This being substantially a description of my present conception, it will be noted that the transverse crimps or corrugations C may be varied somewhat without destroying the continuity of my design, and, if desired, the ends E may be relieved of their plainness—as, for example, by crimping them to correspond with the opposite sides of the pan, which they connect.

Having thus described my invention, what I claim, and desire to secure by Letters Patent, is—

The design for a baking-pan, herein shown and described.

In testimony whereof I subscribe my signature in the presence of two witnesses.

WILLIAM H. MULLINS.
